KNITTING MACHINE

Harold E. Houseman, Laconia, N. H., assignor to
Scott and Williams, Incorporated, Laconia,
N. H., a corporation of Massachusetts

Original application March 28, 1939, Serial No.
264,533. Divided and this application August
3, 1939, Serial No. 288,083

7 Claims. (Cl. 66—43)

This invention relates to a knitting machine, and particularly to the adjustments of the cams thereof.

This application is a division of my application Serial No. 264,533, filed March 28, 1939.

As indicated more fully in said patent application, the machine of the present invention may be regarded as an improvement on the machine of the Scott Patent 1,641,101, dated August 30, 1927, various features of which it embodies. The improved machine is particularly designed for the production of a split foot stocking in which the leg is knit two-feed so that at the beginning of split knitting above the heel no yarn or feed must be introduced. Specifically, there is provided such a stocking in which there is provided a rib top knit continuously with such leg.

The present division of said parent application is directed to the provision of stitch cam controlling means for securing proper adjustments and balance of stitches for the production of a satisfactory product.

The object just indicated, as well as other objects, particularly relating to details of the mechanism, will become apparent from the following description, read in conjunction with the accompanying drawings, in which:

Figure 1 is a fragmentary vertical section through the needle cylinder and associated parts of the machine, illustrating particularly the association of a rib needle dial with the needle cylinder;

Figure 2 is a partial inside development of the needle cams;

Figure 3 is a perspective view showing the various cams associated with the auxiliary feed of the machine and their operating elements;

Figure 4 is a vertical section taken through certain of the operating parts of the auxiliary feed cams;

Figure 5 is a plan view illustrating particularly the needle cam operating elements;

Figure 6 is a fragmentary vertical section showing particularly certain stitch controlling elements and taken on the plane indicated at 6—6 of Figure 5; and

Figure 7 is an elevation of the parts illustrated in Figure 6.

The stocking which the present machine is adapted to produce comprises a setting up course following the formation of which there are produced a number of welt-forming courses providing, as described in said Scott Patent 1,641,101, a turned plain knit welt. Following the production of this welt, there is formed the rib top 55 foot. The nature of certain of the special ele-

which is, in turn, followed by a series of ribbed loose courses. Following the formation of these loose courses, plain fabric is knit to form the extended top using the yarn which was knit to form the rib top. Then the leg is knit with change of yarn, preferably using two feeds so that two courses are produced for each revolution of the needle cylinder.

Such two-feed knitting continues until the 10 high splice is reached, whereupon split knitting occurs with the formation of the high splice and an upper instep portion of the stocking. Reciprocation of the needle cylinder takes place at this time. Following completion of the high 15 splice a yarn change may take place and formation of the heel proceeds, the heel having the conventional narrowed and widened portions. Split knitting is then resumed to form the foot and instep. At the end of the foot there are 20 formed by rotary knitting a plurality of advance toe courses followed by a reciprocatory knit toe having narrowed and widened portions. The stocking is then finished with the formation by rotary knitting of the loopers rounds.

25 Referring first to Figure 1, there are illustrated therein certain of the basic parts of the machine which are substantially similar to the parts more fully illustrated in Scott Patent 1,641,101, referred to above. The needle cylinder 34 is 30 preferably of an elongated type having slots in which slide not only the needles 36, but upper and lower jacks illustrated in said parent application. The sinker dial of the machine is illustrated at 44 and carries in slots therein in the conventional fashion web holders or sinkers indicated generally at 46. Sinker actuating cams of substantially conventional type are provided.

Above the needle cylinder there is located the 35 rib needle dial 52, which carries the two-part rib needles 54, 56 of the type specifically disclosed in said Scott patent. The rib needle dial is driven through the conventional bevel gearing and vertical shaft in synchronism with the needle cylinder.

40 The needle cylinder is movable relatively to the needle dial as described in said Scott patent. Additionally, this means is used to adjust the position of the needle cylinder for the required length of stitch at the main feed by providing for fine adjustment of the cam following screws of the Scott arrangement.

The present machine differs from the machine 45 of said Scott patent by reason of the provision for split foot knitting through the high splice and 50 foot. The nature of certain of the special ele-

ments of this machine which are of interest in the present application may be best understood by referring to Figure 2, which shows in developed form the principal needle actuating cams.

At the main feed point of the machine there are located the top center cam 62 and lower center cam 64, flanked by the forward and reverse stitch cams 66 and 68, respectively. Below stitch cam 66 is located the cam 70 which checks the needles against overrun, while below reverse stitch cam 68 there is located a cam 74 adapted to check overrun of the needles depressed by the reverse stitch cam 68. Beyond the cam 70 in the direction of forward movement of the needles is the needle raising cam 72. During reverse knitting an extension of the cam 74 provides for needle raising.

Cams 76 and 78 are arranged to complete the lowering of the needles which are picked downward by a conventional lowering picker, not shown. The cam 80 levels the needles properly for engagement with this picker.

Of the cams so far described, all are fixed with the exception of cams 66 and 70, which are axially movable.

The cams associated with the auxiliary or instep feed comprise the top center cam 92, forward and reverse stitch cams 94 and 96, reverse and forward deflecting cams 98 and 100, forward and reverse raising cams 102 and 104, and forward and reverse lower needle arresting cams 106 and 108, respectively. Of these cams, top center cam 92 and raising cams 102 and 104 are radially movable. The other cams 94, 96, 98, 100, 106 and 108 are both radially movable and axially adjustable.

The needles 36 carried by the cylinder are of conventional type divided into the usual sole and instep series of which the instep series are provided with long butts and of which the sole series are provided with short butts, with the exception of suture needles located at the ends of the sole series and provided with intermediate butts. It is usual to have the sole needles occupy half the cylinder and the instep needles the other half. One or more of the suture needles may be provided at each end of the short butt series.

Referring to Figures 3 and 5, it will be noted that the cam 102 is carried by the up-turned end 130 of a radially movable slide 132, which is held on the upper bed plate 131 by a cover 133, which has a milled slot adapted to receive for sliding movements the slide 132. A spring 134 urges the slide inwardly toward the needle cylinder. It is caused to move outwardly by engagement, with a stop screw 136 carried by the slide, of a lever 138, pivoted on the plate 131 and having a lower arm 142 link-connected to a lever 144, adapted to be controlled by suitable cams on the main cam drum of the machine.

A yoke 146 is provided with a milled slot and is arranged to embrace the up-turned end 130 of the slide 132 so as to be movable upwardly and downwardly with respect thereto. It is held in proper relationship with the up-turned end 130 by being secured to a bridging portion of the cam 106. The yoke 146 has an upright extension 150 which carries cams 94 and 98. The yoke 146 is urged upwardly by a spring, which is not shown, but corresponds to the spring 172 illustrated in Figure 4, cooperating with a corresponding yoke 168. The yoke is held downwardly in adjusted position by means of a finger 148, to which reference will be made hereafter.

By reason of the mounting of the yoke and the slide, it will be evident that the cam 102 has only radial movements, while the cams 106, 94 and 98 partake of the radial movements of cam 102, but are independently vertically adjusted. The cams on the other side of the center of the auxiliary feed group are similarly mounted. There is provided a slide 154 having an up-turned end 152 and arranged to slide on the upper bed plate under the guidance of a cover member 156. A spring 158 urges the slide 154 inwardly and outward movements are imparted thereto at proper times by means of a lever 162, which abuts a stop screw 160 adjustable in the slide 154 and is actuated through an arm 164, link-connected to a lever 166 acted upon by suitable cams on the main cam drum. On the up-turned end 152 of the slide 154 is the yoke 168, urged upwardly by spring 172 and carrying the cam 108 below the cam 104, which is secured to the end 152 of the slide. The yoke 168 is held on end 152 by cam 108 and has an upward extension 170 for supporting the cams 96 and 100. Thus this second group of cams at the auxiliary feed point is mounted in a fashion similar to the group on the other side, all of the cams having common radial movements with slide 154, while the cams 108, 96 and 100 are vertically adjustable. A finger 174 similar to finger 148 limits upward movement of the yoke 168 under the action of its spring 172.

The center cam 92 of the auxiliary group is carried by a lever 178, which is pivoted at 176 on the cover plate 156. This lever is provided with an abutment screw 182 adapted to engage a stop pin 184 carried by the plate 156 under the action of a spring 186 to limit inward movement of the cam 92. An adjustable abutment screw 180 is carried by the lever 178 so as to be engageable by the yoke 168 when the slide 154 is moved to its outermost position. When that occurs, the center cam 92 will be withdrawn from proximity to the needle cylinder so as to miss engagement with needle butts.

The fingers 148 and 174 which limit upward movements of the yokes 146 and 168 are carried, respectively, by arms 188 and 190, which form portions of bell cranks pivoted at 191 in a bracket attached to the upper bed plate 131. The depending arm of the first bell crank which has the horizontal arm 188 is indicated at 192 and is provided with adjustable abutment screws 194, 196 and 198, respectively, adapted to be engaged by a cam 200, which is provided with slots embracing studs 202 at the periphery of the lower bed plate 204, the arrangement being such that the cam 200 has a substantial arc of movement about the edge of the bed plate. The cam 200 is provided with a pin 206 which is engaged and moved by the end of a lever acted upon by suitable cams on the main cam drum. The screws 194, 196, and 198 may be differentially projected so as to secure various adjustments of position of the yoke 146, depending upon the position of the cam 200. The arm 192 is provided with a lateral extension 212 overlapping the depending arm 216 of the second bell crank 190 and adapted to be engaged by an adjustable screw 214 carried by the latter arm. This screw is preferably provided with a grooved head engageable by a spring pressed detent 218, so that it may be forcibly adjusted, but will be definitely held in adjusted position until substantial force is exerted to turn it against the holding action of the detent. As will be evi-

dent, hereafter, the two yokes 146 and 168 will, in general, partake of the same adjustments for different conditions, but for stitch balancing purposes, must be adjusted with respect to each other. The arrangement just described provides for such condition.

The control of the cams forming the subject-matter of this application takes place first in the formation of the stocking after completion of the extended top, when the auxiliary yarn finger is brought into action. This yarn finger carries a fine yarn suitable for the formation of the leg and corresponding in fineness and type to the yarn at the main feed which will also form the leg. For the purpose of increasing the rapidity of production and also minimizing the appearance which might be due to unevenness of the yarns, two courses of the leg are knit in every revolution of the needle cylinder, i. e., the leg is knit two-feed. Accordingly, at this time yarns are brought into action at both the main and auxiliary feed. All of the cams at the auxiliary feed are rendered active. The stitch adjusting cam 200 will now be in a position (which it may have idly occupied heretofore) to engage the proper screw in the lever 192 to adjust the stitch cam 94, to the position necessary to balance the stitches formed at the auxiliary feed with those formed at the main feed, while both yarns produce the leg. All of the needles now pass through knitting waves at both the main and auxiliary feeds, and consequently the leg is produced in two-feed fashion.

Following the formation of the leg the production of the high splice is begun with the simultaneous production of the instep portion of the stocking. In the formation of these portions of the stocking, the instep needles take yarn at the auxiliary feed to knit the instep portion while the sole needles take yarn at the main feed to knit the high splice. The suture needles take yarn at both feeds. Knitting is now accomplished during reciprocation of the needle cylinder and knitting, therefore, takes place during both forward and reverse movements of the needles.

A high splice yarn is now substituted at the main feed for the leg yarn. The various cams at the auxiliary feed, with the exception of the center cam 92, are partially withdrawn so as to engage only the long butt and suture needles, but miss the short butt needles.

The needles now pass through the cams as described in said parent application Serial No. 264,533.

During the formation of this portion of the fabric, the cam 200 will have been moved to a position to adjust the stitch cams at the auxiliary feed to produce stitches through the instep, (which is knit on one feed only) corresponding to the stitches formed in the leg by both feeds so that a uniform appearance is provided from the leg into the instep. The two stitch cams 94 and 96 are adjusted relatively to each other by adjustment of the screw 214. In order to secure a proper stitch condition through the high splice a relative adjustment of the stitch cams 68 and 66 at the main feed is also effected. The proper stitches are caused to be produced by fixed cam 68 by vertical adjustment of the needle cylinder by control of the means illustrated in said Scott patent.

Following completion of the high splice, reciprocation is continued for the formation of the heel. The instep yarn continues to extend

from its actively positioned finger to the suture needle which last received it and a suitable take-up sweep of conventional character is active to control it. The cams at the auxiliary feed are now completely withdrawn to such extent as to withdraw center cam 92 with them. Withdrawal of cam 92 is necessary, since it will otherwise lower needles which are picked down and thereby may cause them to seize the instep yarn which is idling back and forth.

Following the formation of the heel, the production of the split foot now proceeds with the restoration of the various cams to the position they occupied in the formation of the high splice, and the movements of the various needles and sinkers in the formation of the split foot are the same as they were during the formation of the high splice. Since a different yarn may be used in the split foot as compared with the yarn used for the formation of the high splice, the cam 200 may be adjusted to a third position to provide proper balance of the stitches in the instep portion of the stocking to cause them to correspond to the stitches formed in the upper instep portion adjacent the high splice.

At the end of the formation of the split foot rotary knitting is resumed to provide knitting of all of the needles at the main feed to produce the ring toe. Accordingly, the cams at the auxiliary feed are withdrawn. The stocking is then completed in conventional fashion, no further knitting at the auxiliary feed occurring.

What I claim and desire to protect by Letters Patent is:

35. 1. In a knitting machine, a needle cylinder carrying a circular series of needles, a stitch cam for lowering needles as they travel in one direction to cause them to draw loops of yarn, a second stitch cam for lowering the needles as they travel in the opposite direction to cause them to draw loops of yarn, means for relatively adjusting said stitch cams to balance the loops drawn under their action, and pattern means for automatically moving said stitch cams in unison to vary the size of the balanced loops drawn.

40. 2. In a knitting machine, a needle cylinder carrying a circular series of needles, a stitch cam for lowering needles as they travel in one direction to cause them to draw loops of yarn, a second stitch cam for lowering the needles as they travel in the opposite direction to cause them to draw loops of yarn, means for relatively adjusting said stitch cams to balance the loops drawn under their action, means for moving said stitch cams in unison to vary the size of the balanced loops drawn, and means for independently moving said stitch cams toward and away from the needles.

45. 3. In a circular knitting machine, a needle cylinder carrying a circular series of needles, means for feeding yarn to the needles, a pair of stitch cams located adjacent said feeding means, a pair of slides each carrying one of said stitch cams and being radially movable with respect to the needle cylinder, said stitch cams being vertically movable on their slides, and means for effecting movements of said stitch cams both radially and axially with respect to the needle cylinder.

50. 4. In a circular knitting machine, a needle cylinder carrying a circular series of needles, a main knitting feed, and an auxiliary knitting feed, the latter including a pair of stitch cams which with respect to the needle cylinder are

independently axially adjustable for stitch balancing, axially movable in unison for stitch adjustment, and also movable radially toward and from the needle cylinder to engage selectively needles thereof.

5. In a knitting machine, a needle cylinder carrying a circular series of needles, a stitch cam for lowering needles as they travel in one direction to cause them to draw loops of yarn, a second stitch cam for lowering the needles as they travel in the opposite direction to cause them to draw loops of yarn, said stitch cams being operated by separate means which are relatively adjustable to balance the loops drawn by the two stitch cams and which are movable in unison to vary the size of the balanced loops drawn.

6. In a knitting machine, a needle cylinder carrying a circular series of needles, a stitch cam for lowering needles as they travel in one direction to cause them to draw loops of yarn, a second stitch cam for lowering the needles as they travel in the opposite direction to cause them to draw loops of yarn, one of said stitch

cams being operated by a lever, the other of said stitch cams being operated by a second lever which is mounted on the first named lever, and adjustable means for varying the relative positions of said levers so that the loops drawn by the two stitch cams may be balanced.

7. In a knitting machine, a needle cylinder carrying a circular series of needles, a stitch cam for lowering needles as they travel in one direction to cause them to draw loops of yarn, a second stitch cam for lowering the needles as they travel in the opposite direction to cause them to draw loops of yarn, one of said stitch cams being operated by a lever, the other of said stitch cams being operated by a second lever which is mounted on the first named lever, adjustable means for varying the relative positions of said levers so that the loops drawn by the two stitch cams may be balanced, and means for moving the two levers as a unit to vary the size of the balanced loops drawn.

HAROLD E. HOUSEMAN.
